DESIGN FOR A SLIP

Esther Cadous, New York N. Y.

Application October 9, 1940, Serial No. 95,733

Term of patent 7 years

To all whom it may concern:

Be it known that I, Esther Cadous, a citizen of the United States of America, residing in the city of New York, county of New York, and State of New York, have invented a new, original, and ornamental Design for a Slip, of which the following is a specification, reference being had to the accompanying drawing, forming part thereof.

Fig. 1 is a front view of a slip showing my new design.

Fig. 2 is a rear view thereof.

I claim:

The ornamental design for a slip, as shown.

ESTHER CADOUS.
